PUMP VALVE MOUNTING

Henry E. Brandt, St. Paul, Minn., assignor to
 Dobbins Manufacturing Company, North St.
 Paul, Minn., a corporation of Minnesota

Application June 7, 1937, Serial No. 146,764

2 Claims. (Cl. 251—144)

This invention relates to the construction of a valve mounting for a pump cylinder and while the invention is capable of many uses and applications, it has been developed particularly for an air pump used in connection with sprayers.

It is an object of this invention to provide a simple assembly of closure member and valve which can be inexpensively produced and secured in the pump cylinder.

10 It is another object of the invention to provide a simple assembly of diaphragm and valve for the pump cylinder, which parts can be placed in the cylinder without the walls of the cylinder being cut or perforated.

15 It is a further object of the invention to provide a simple valve construction, one which will operate properly and which comprises a spring, said spring acting to hold the valve to its seat and also acting to hold the valve-carrying means in position.

20 It is still another object of the invention to provide in combination with a diaphragm extending across the cylinder and secured therein, said diaphragm having an opening therethrough with 25 a valve seat around said opening, a valve-carrying member supported by said diaphragm and easily and quickly removable therefrom with said valve.

25 These and other objects and advantages of the invention will be fully set forth in the following description made in connection with the accompanying drawing in which like reference characters refer to similar parts throughout the several views and in which:—

30 Fig. 1 is for the most part a central vertical section through the pump cylinder and parts therein, a portion of the cylinder being shown in side elevation;

35 Fig. 2 is a view in side elevation of the cylinder, a portion being broken away to show some of the parts therein;

40 Fig. 3 is a bottom plan view of Fig. 1; and

45 Fig. 4 is a vertical section taken on line 4—4 of Fig. 1 as indicated by the arrows.

50 Referring to the drawing, a pump cylinder 10 is shown in which is reciprocable a plunger 11. This plunger is shown as having a flange 11a extending around and fitting in cylinder 10 so that the plunger is cup-shaped. A plate 12 overlies the top of said plunger and there is a plate 13 engaging the underside of said plunger. Plates 12 and 13 are apertured to have plunger rod 14 extend therethrough, said rod being threaded to receive nuts 15 and 16 respectively engaging plates 12 and 13 to hold the same against plunger 11 and

secure the same in place. The structure so far described is old and in common use.

In accordance with the present invention, a diaphragm 17 is provided of substantially circular form extending across the entire area of cylinder 10, the same having a flange 17a extending circumferentially thereabout of a size to fit tightly in cylinder 10 and engage the inner wall thereof. Diaphragm 17 is shown as having its top slightly curved in convex form and said diaphragm will 15 be secured in said cylinder by connecting flange 17a to the cylinder in any suitable manner as by soldering or welding. Diaphragm 17 has a central aperture 17b therethrough and a valve seat 17c is formed on the underside of said diaphragm, 20 said seat surrounding said aperture. In the embodiment of the invention illustrated, seat 17c is formed by bending downwardly the metal of the diaphragm which surrounds said aperture, thus forming a short cylinder, the lower edge of which 25 forms the valve seat. Flange 17a has a pair of lugs 17d formed thereon at opposite sides thereof and extending inwardly toward the axis of the cylinder and substantially perpendicular thereto. A bar 18 is provided, the opposite ends of which 30 rest upon lugs 17d respectively. Said ends of bar 18 have pressed therein a groove 18a, the sides of which extend along the sides of the lugs 17d so that said lugs are disposed in said grooves and lateral movement of said bar is prevented. Bar 35 18 has formed at the central portion thereof a cup 18b having a chamber or depression 18c therein. A compression coil spring 19 is seated in cup 18b having one end engaging the bottom of said cup and the upper end of said spring carries a cup- 40 like plate 20. Plate 20 has a central depressed portion 20a in the bottom thereof which extends into the top of spring 19 so that the upper portion of said spring extends about said depression and holds member 20 in position centrally of said 45 spring. A disk 21 of yielding material, preferably resilient, is carried in member 20. Disk 21 is preferably made of rubber or similar material and forms a valve adapted to engage the valve 50 seat 17c to close aperture 17b. A pin 22 extends centrally through plate 20, through the bottom of cup 18b centrally thereof and passes centrally through spring 19. Pin 22 has an enlarged portion 22a disposed in the depressed portion 20a of plate 20, the upper surface of said portion engaging the bottom of disk 21. Pin 22 also has an enlarged portion or head 22b below cup 18b and engaging the bottom of the latter.

In operation, it will be seen that spring 19 will press valve disk 21 against the valve seat 17c so 55

that aperture 17b is normally closed. Upward movement of plunger 11 can take place without any air being drawn into the cylinder and said movement will cause the outside air to press disk 21 more firmly against its seat. Downward movement of plunger 11 will force air through aperture 17b, compressing spring 19 so that said air may be discharged from the cylinder. It will be noted that when spring 19 is compressed pin 22 will move through the bottom of cup 18b. It will also be noted that spring 19 not only urges disk 21 against its seat but also acts to press bar 18 against the lugs 17d. This action is caused by the fact that lugs 17d are rigid with the diaphragm 17 against which valve disk 21 reacts. At the same time bar 18 can be readily removed by pressing the same upwardly so that the bar can be rotated to bring the ends thereof and grooves 18a out of alignment with the lugs 17d. The bar 20 is then readily removable with the valve disk 21 and the other parts. Pin 22 and specifically its enlarged end 22b acts to limit the movement of plate 20 and valve disk 21 away from bar 18 so that the same constitute one unitary assembly 25 when removed from diaphragm 17. Enlargement 22b thus forms a stop to limit the movement of member 20 away from bar 18. The valve 21 is thus very readily removable for replacement, cleaning or other purpose.

30 From the above description it is seen that applicant has provided a very simple and yet very efficient valve structure. All of the parts can be made by punching operations and need only to be assembled. All parts are carried by the diaphragm 17 and it is unnecessary to cut or deform the cylinder wall. The valve as stated can be very easily and quickly removed and replaced in position. The action of the valve is very efficient as the spring 19 holds the disk 21 in position 40 axially of the cylinder. The parts of the device are quite few, easily produced and the structure is quite inexpensive. The device has been amply

demonstrated in actual practice, found to be very successful and efficient and is being commercially made.

It will, of course, be understood that various changes may be made in the form, details, arrangement and proportions of the parts, without departing from the scope of applicant's invention, which generally stated, consists in a device capable of carrying out the objects above set forth in the parts and combinations of parts disclosed and defined in the appended claims. 5 10

What is claimed is:

1. A valve structure assembly comprising a diaphragm of circular outline formed of sheet metal and having a cylindrical rim thereabout adapted to fit and be secured in a cylindrical member such as a sprayer pump cylinder, said diaphragm having a central aperture therethrough with a projecting cylindrical flange thereabout forming a valve seat, said rim having diametrically opposite 20 lugs extending toward each other and spaced below said diaphragm and flange, a bar extending between and supported upon said lugs having a length less than the inner diameter of said rim, said bar having a central spring-receiving recess, 25 a yielding valve member positioned to engage said flange, a valve carrier for said valve having a stem projecting therefrom and through said bar in said recess, a compression coiled spring seated in said recess engaging said bar at one end and said carrier at its other end and acting to hold said valve against said valve seat and to hold said bar against said lugs, said stem having a stop means thereon below said bar to retain said stem and valve carrier when said bar is removed from said 35 lugs.

2. The structure set forth in claim 1, said bar having recesses on its underside in which said lugs are disposed whereby circumferential movement of said bar about said stem is prevented. 40
